UNITED STATES PATENT OFFICE.

G. BURNS PERSONS, OF DARFUR, MINNESOTA.

WOVEN-WIRE CLAMP.

1,095,025.

Specification of Letters Patent.

Patented Apr. 28, 1914.

Application filed May 5, 1913. Serial No. 765,513.

To all whom it may concern:

Be it known that I, G. BURNS PERSONS, a citizen of the United States, residing at Darfur, in the county of Watonwan and 5 State of Minnesota, have invented certain new and useful Improvements in Woven-Wire Clamps; and I do hereby declare the following to be a full, clear, and exact description of the invention, such as will enable others skilled in the art to which it 10 appertains to make and use the same.

My invention has for its object to provide an improved clamp especially adapted for use in conjunction with wire stretchers in 15 putting up woven wire fences.

To the above end, generally stated, the invention consists of the novel devices and combinations of devices hereinafter described and defined in the claims.

20 The invention is illustrated in the accompanying drawings, wherein like characters indicate like parts throughout the several views.

Referring to the drawings: Figure 1 is 25 a view in side elevation, showing the improved clamp secured to the pulling cables of a pair of wire stretchers and applied to a woven wire fence; Fig. 2 is an edge elevation of one end of the improved clamp; and 30 Fig. 3 is a view in transverse section, taken on the line $\alpha^3 \alpha^3$ of Fig. 1.

The numerals 1 and 2 indicate a pair of clamping bars. To the inner face of the clamping bar 1 is secured a gripping bar 3, as shown, preferably angle-shaped in cross section, with its flanges secured to and set part way into said clamping bars. Seated and rigidly secured in shallow grooves 4, formed in the inner face of the 40 clamping bar 2, is a pair of vertically extended gripping bars 5 that are, as shown, preferably rectangular in cross section. The gripping bars 3 and 5 extend the full length of the clamping bars 1 and 2, and the bars 5 are laterally spaced apart to permit the vertex of the bar 3, which is located at the intermediate portion of the clamping bar 1, to project between the bars 5, when the clamping bars 1 and 2 are pressed together. 45 Obviously, these gripping bars 3 and 5 form three point contacts that extend the full length of the clamping bars 1 and 2, and kink or bend the longitudinal wires of a woven wire fence α .

50 The clamping bars 1 and 2 are secured to the outer ends of the pulling cables b of a

pair of wire stretchers, not shown, by means of grapple hooks c , that embrace the longitudinal outer edges of the clamping bars 1 and 2. For the purpose of this case, it is 60 not thought necessary to show the wire stretchers, as they form no part of the present invention.

A pair of clamps, each comprising an inner and an outer yoke 6 and 7, respectively, is provided for pressing the bars 1 and 2 together. These clamps are located one at each end of the clamping bars 1 and 2 but, in case the bars 1 and 2 are extremely long, an intermediate clamp may be used. 65 The inner yokes 6 embrace the clamping bar 1, and the free ends of their prongs are bent laterally inward to afford retaining lugs 8, that are slidably mounted in grooves 9 formed at the inner longitudinal edges of 70 the clamping bar 1. The prongs of the inner yokes 6 are provided, at their longitudinal edges, with outwardly extended flanges 10, which embrace and hold the prongs of the outer yokes 7 for straight line 75 endwise sliding movement. The outer yokes 7 embrace the two clamping bars 1 and 2, and the free ends of their prongs are bent laterally inward to afford retaining lugs 11 that slidably engage the outer longitudinal 80 edge portions of the clamping bar 2.

To permit the clamping bar 2 to be removed laterally from the clamping bar 1 and out of engagement with the outer yokes 7, one prong of each of said yokes 7 is provided with a hinge joint 12, which permits the retaining lug 11 of said prong to swing into and out of locking engagement with the clamping bar 2. A set screw 13 is provided for each outer yoke 7 and has screw 90 threaded engagement with the transverse portion thereof. The inner ends of said screws impinge against the transverse portions of the clamping yokes 6. The outer yoke 7 is held for limited endwise sliding 95 movement, with respect to the inner yoke 6, by means of a screw stud 14 and a set screw 15. The intermediate portions of these screws 14 and 15 project through longitudinally extended slots 16 formed in the prongs 100 of the outer yokes 7, and their inner ends have screw threaded engagement with the prongs of the inner yokes 6. The set screws 15 project completely through the prongs of the yokes 6 to which they are applied, impinge against the clamping bar 1, and afford 105 means for securing the yokes 6 in different

longitudinal adjustments on the clamping bars 1 and 2.

From the above description, it is evident that all of the longitudinal wires of the fence *a* are securely held by the improved clamp, thereby preventing the fence from pulling out of shape during the stretching of the same by the pulling cables *b*. By applying a pulling cable to each end of the improved clamp, different tensions may be placed thereon, to keep the vertical wires of the fence in their proper positions. In securing the improved clamp to a woven wire fence, the yokes 6 are first secured in proper vertical adjustment on the clamping bar 1, by the set screws 15. The clamping bar 2 is then placed in position within the yokes 7, and the two bars 1 and 2 are drawn together by means of the set screws 13. While the clamping bars 1 and 2 are being secured together, the gripping bar 3 bends or kinks the engaged portion of the fence *a* between the gripping bars 5, thereby securing the same against slipping.

25 The above described device, while extremely simple and of comparatively small cost to manufacture, is thought to be highly efficient for the purpose had in view.

What I claim is:

30 1. A device of the kind described, comprising a pair of coöperating clamping bars having, on their opposing faces, gripping bars, an inner clamping yoke mounted on one of said bars, an outer clamping yoke 35 having, on its prongs, retaining lugs and embracing said bars, the prongs of said outer yoke being mounted for endwise sliding movement, with respect to said inner yoke, and an adjusting device between said 40 two yokes, in combination with a pulling device applied to said bars.

45 2. A device of the kind described, comprising a pair of coöperating clamping bars having, on their opposing faces, gripping bars, an inner clamping yoke mounted on one of said bars, an outer clamping yoke having, on its prongs, retaining lugs and embracing said bars, the prongs of said outer yoke being mounted for endwise slid-

ing movement, with respect to said inner 50 yoke, and an adjusting device between said two yokes, one of the prongs of said outer yoke having a hinged section, in combination with a pulling device applied to said bars. 55

3. A device of the kind described, comprising a pair of coöperating clamping bars having, on their opposing faces, gripping bars arranged for three point contact with the wires of a fence, an inner clamping yoke 60 mounted on one of said bars, for longitudinal adjustments thereon, means for securing said inner yoke in different longitudinal adjustments, an outer yoke having, on its prongs, retaining lugs and embracing said 65 two bars, the prongs of said outer yoke being mounted for endwise sliding movement, with respect to the inner yoke, and an adjusting device between said two yokes, in combination with a pulling device applied 70 to the said bars.

4. A device of the kind described, comprising a pair of coöperating clamping bars having, on their opposing faces, gripping bars arranged for three point contact with 75 the wires of a fence, an inner clamping yoke mounted on one of said bars, for longitudinal adjustment thereon and having, on its prongs, retaining lugs, means for securing said inner yoke in different longitudinal 80 adjustments, an outer yoke having, on its prongs, retaining lugs and embracing said two bars, the prongs of said outer yoke being mounted, for endwise sliding movement, on the inner yoke, an adjusting device between said two yokes, and means for limiting the endwise sliding movement of said 85 outer yoke with respect to said inner yoke, one of the prongs of said outer yoke having a hinged section, in combination with a 90 pulling device applied to the said bars.

In testimony whereof I affix my signature in presence of two witnesses.

G. BURNS PERSONS.
